DESIGN FOR A BOTTLE

Francois Victor Klotz, New York, N. Y., assignor to Pinaud, Incorporated, New York, N. Y., a corporation of New York

Application May 17, 1934, Serial No. 51,826

Term of patent 14 years

To all whom it may concern:

Be it known that I, FRANCOIS VICTOR KLOTZ, a citizen of the Republic of France, residing in New York, in the county and State of New York, have invented a new, original, and ornamental Design for a Bottle, of which the following is a specification, reference being had to the accompanying drawing, forming part thereof.

Fig. 1 is a front view in elevation of the bottle and cap embodying my new design.

Fig. 2 is a rear view of the bottle of Fig. 1.
Fig. 3 is a top plan view of the device of Fig. 1.
Fig. 4 is a top plan view of the bottle shown in Fig. 2, with the cap removed.

I claim:

The ornamental design for a bottle as shown.

FRANCOIS VICTOR KLOTZ.
